Primary Examiner — Michelle E. Wilson*Assistant Examiner* — Clese Moore, Jr.(74) *Attorney, Agent, or Firm* — Bycer & Marion, PLC; Matthew L. Bycer; Michael B. Marion(57) **CLAIM**

I claim the ornamental design for a wraparound step cover, as shown and described.

DESCRIPTION

FIG. 1 illustrates a lower perspective view of a wraparound step cover;

FIG. 2 illustrates an upper perspective view of the present invention.

FIG. 3 illustrates a front side view of the present invention.

FIG. 4 illustrates a rear side view of the present invention.

FIG. 5 illustrates a left side view of the present invention.

FIG. 6 illustrates a bottom plan view of the present invention; and,

FIG. 7 illustrates a top plan view of the present invention. The drawings set forth a unique design for a wraparound step cover.

The broken lines shown in the drawings represent portions of the wraparound step cover and attachments that form no part of the claimed design.
